United States Patent

Des. 235,820
Patented July 15, 1975

235,820

NECKTIE

Arnold Brown, Rte. 1, Box 13B, Poteau, Okla. 74953

Filed Jan. 8, 1974, Ser. No. 431,596

Term of patent 14 years

Int. Cl. D2—02

U.S. CL. D2—351

FIG. 1 is a front plan view of a necktie showing my new design;

FIG. 2 is a bottom edge view thereof;

FIG. 3 is a rear plan view; and

FIG. 4 is a top edge view.

I claim:

The ornamental design for a necktie, substantially as shown.
